UNITED STATES PATENT OFFICE.

FREDERICK C. WERNER, OF WATERTOWN, WISCONSIN.

APPLIANCE FOR TREATING GOITER.

1,190,831.

Specification of Letters Patent. Patented July 11, 1916.

Application filed August 9, 1915. Serial No. 44,564.

To all whom it may concern:

Be it known that I, FREDERICK C. WERNER, a citizen of the United States, residing at Watertown, in the county of Jefferson and State of Wisconsin, have invented a certain new and useful Improvement in Appliances for Treating Goiter, of which the following is a full, clear, concise, and exact description, reference being had to the accompanying drawings, forming a part of this specification.

My invention relates to appliances for treating goiter, and has for its object the provision of such a device whereby galvanic currents adaptable for electrotherapeutic uses such for instance as above outlined may be produced.

It is well known in the medical field that uni-directional currents, or galvanic currents, have been employed effectively in the treatment of goiter and that this disease has also been successively treated by the use of mercury, zinc, and iodin compounds.

In the electrogalvanic treatment of goiter a limitation has been found where special electrodes with external sources of current are used, in that the treatment is applied intermittently for a few minutes at a time and requiring many treatments.

The purposes of this invention are to embody a means of generating galvanic currents in contact with the skin, in the presence of mercurous iodid and calcium chlorid; the device consisting of a chain or necklace of ornamental appearance and of easy and comfortable application, so that the wearer can apply the treatment with a minimum of discomfort and inconvenience.

The appliance embodies a multiplicity of galvanic couples consisting of zinc and copper plates connected together metallically, with spacers between, consisting of insulating beads of amber, glass, insulating composition or other similar materials. These couples become active by the edges of the zinc and copper disks coming in contact with the skin, which has been prepared by the application of an ointment containing suitable materials, such as a combination of mercurous iodid and calcium chlorid. The skin thus treated constitutes the electrolytic portion of the galvanic cell. This establishes a path for the current and a mild galvanic current will thus flow. The electro-chemical action of a cell such as this can be readily understood if we would as-

sume a jar from which two electrodes project, one of which could be a zinc anode and the other a copper cathode and these two electrodes were connected together metallically by a suitable conductor. A suitable electrolyte would then be placed in the jar consisting of a calcium chlorid and mercurous iodid. The current would then flow from the anode through the electrolyte to the cathode. The effect of this current is to attract toward the anode the chlorin and the iodin ions, and to attract toward the cathode the mercury and calcium ions. There will thus be formed at the anode zinc iodid and zinc chlorid, while mercury tends to be deposited at the cathode. It will thus be seen that there is a chemical action at the electrode surfaces, combined with a migration action on the substances which are in solution.

In the electro-therapeutic device the electrolyte consists of the skin, which is in itself slightly conductive but which is rendered more conductive by the presence of calcium chlorid and mercurous iodid. The chief purpose of the mercurous iodid is to furnish materials having suitable medicinal properties, while the chief function of the calcium chlorid is, due to its hygroscopic property, to attract moisture. The calcium chlorid thus combined with water furnishes the electrolyte by which the electrolytic action can be initiated. The formation of zinc iodid and zinc chlorid likewise produces compounds which are hygroscopic, which likewise attract moisture and tend to add to the conductivity of the electrolytic part of the circuit. The flow of current which is thus established exercises the well known cataphoretic effect, causing certain constituents to travel through the skin in the direction of the cathode, or producing cataphoresis. I thus have here the presence of suitable medicinal materials combined with a uni-directional current which causes these materials to pass through the skin to thus become readily absorbed in the circulatory system. This galvanic chain is used in the form of a belt or necklace which is strapped or tied around the body in such a manner that the effective portion thereof shall overlie the affected part, and it differs further from other similar devices in not providing any electrolyte or other source of current produced within the belt or chain itself, such electrolyte being provided by means of medicament which is spread upon the sur-

face of the skin over the affected part, the electrolysis accelerating the desired effect and causing the penetration of such medicament. In the case of goiter, for which the 5 appliance is more particularly intended, the necklace is divided in the middle in such manner as to spread on both sides of the enlargement, thus producing both a physical and medical effect; viz. to hold the necklace in place and to distribute the medicative 10 action of the appliance.

The nature of the invention will be best understood by consideration of the following detailed description thereof taken in 15 connection with the accompanying drawing, in which—

Figure 1 is a perspective view of the appliance in its approved form, and Fig. 2 20 is a longitudinal section through a few of the links thereof on an enlarged scale.

The reference letters refer to the same parts in both figures.

The necklace as shown comprises a series 25 of beads *a* which may be of spherical or oval form and are of insulating, non-absorptive material, such as celluloid, glass, amber, bone, or composition. These are strung together upon a flexible cord *b*. The cord *b* is terminated by any suitable means 30 for confining the beads thereon such as by metal end pieces *c* and rings *d* engaged therewith. In the middle portion which is in use and is to be disposed over the tissue to be treated, that is to say upon the enlargement constituting the goiter, the cord *b* is divided into two branches, each of 35 which carries a complete set of the beads as shown. On the divided portion, between the beads *a*, are metal disks *f* and *g*, these 40 being respectively of electropositive and electronegative materials, such as zinc and copper, and are alternately disposed as indicated more clearly in Fig. 2. The cord *b* holding the bifurcated portion of the necklace is a metallic conductor such as copper wire which furnishes the necessary metallic 45 connection to the metal disks to make them electro-chemically active.

In use, an ointment is applied to the skin 50 which increases the electrolytic conductivity of the skin and the necklace is then put in place with the bifurcated portion over the affected part so that the disks *f* and *g* rest against the skin. There is thus produced a 55 series of individual cells, the electrolytic portion of which is supplied by the skin and the ointment, no external source of current being required for the therapeutic effect.

60 In Fig. 2 I show the device as applied next to the skin *i* with the layer of ointment *h* in place.

From what has been described it is 65 thought the nature of my invention will be readily clear to those skilled in the art.

Having however thus described one form which my invention may take, what I claim as new and desire to secure by Letters Patent is:

1. A device of the character described 70 consisting of a belt or necklace having a plurality of electrodes arranged in pairs, the two electrodes of each pair occupying different positions in the electro-chemical scale, a metallic cord upon which said electrodes are strung and with which said electrodes have electrical engagement, and beads of insulating material interposed between said electrodes, said electrodes together with their connection forming the external circuit of individual galvanic cells, the protruding portions of said electrodes being adapted in connection with a suitable electrolyte to cause a flow of miniature electric currents of uni-directional current for 85 therapeutic purposes.

2. A device of the character described 90 consisting of a belt or necklace provided with a loop, said loop having a plurality of electrodes arranged in pairs, the two electrodes of each pair occupying different positions in the electro-chemical scale, a metallic cord upon which said electrodes are strung and with which said electrodes have electrical engagement, and beads of insulating material interposed between said electrodes, said electrodes together with their connection forming the external circuit of individual galvanic cells, the protruding portions of said electrodes being adapted in 95 connection with a suitable electrolyte to cause a flow of miniature electric currents of uni-directional current for therapeutic purposes.

3. A device of the character described 100 consisting of a belt or necklace having a plurality of electrodes arranged in pairs, the two electrodes of each pair occupying different positions in the electro-chemical scale, means for metallically electrically connecting adjoining electrodes together, and beads of insulating material interposed between said electrodes, said electrodes together with their connection forming the external circuit of individual galvanic cells, the protruding portions of said electrodes being adapted in 115 connection with a suitable electrolyte to cause a flow of miniature electric currents of uni-directional current for therapeutic purposes.

4. A device of the character described 120 consisting of a belt or necklace provided with a loop, said loop having a plurality of electrodes arranged in pairs, the two electrodes of each pair occupying different positions in the electro-chemical scale, means for metallically electrically connecting adjoining electrodes together, and beads of insulating material interposed between said electrodes, said electrodes together with 125 130

their connection forming the external circuit of individual galvanic cells, the protruding portions of said electrodes being adapted in connection with a suitable electrolyte to cause a flow of miniature electric currents of uni-directional current for therapeutic purposes.

In witness whereof, I hereunto subscribe my name this 22nd day of July, A. D., 1915.

FREDERICK C. WERNER.
